UNITED STATES PATENT OFFICE.

ELVIN S. GOODSPED, OF DETROIT, MICHIGAN, ASSIGNOR TO GENERAL MOTORS CORPORATION, OF DETROIT, MICHIGAN, A CORPORATION OF DELAWARE.

AUTOMATIC ARC-WELDING SHIELD.

Application filed June 10, 1921. Serial No. 476,525.

To all whom it may concern:

Be it known that I, ELVIN S. GOODSPED, a citizen of the United States, and a resident of Detroit, county of Wayne, and State of Michigan, have invented certain new and useful Improvements in Automatic Arc-Welding Shields, of which the following is a full, clear, concise, and exact description, such as will enable others skilled in the art to which the invention relates to make and use the same, reference being made therein to the accompanying drawings, which form a part of this specification.

The invention relates to protective apparatus and more particularly to shields designed to be employed in connection with apparatus in the use of which it is necessary or desirable to protect the attendants or workmen from effects incidental to the operation of the apparatus. As an illustration of one of the many forms of apparatus to which such devices are applicable, reference may be made to means employed in the production and utilization of the electric arc, especially for metal cutting, welding, and like operations, it being well known that the rays emitted by the electric arc are highly injurious to the eyes and likely to cause serious burns upon exposed portions of the skin of those in close proximity to the source of such rays. Accordingly I shall describe herein one embodiment of my invention particularly designed for the protection of workmen engaged in the use of electric arc apparatus.

One of the objects of my invention, therefore, is the provision of means for protecting a workman from injury due to the rays emitted by an electric arc.

A further object is to provide in connection with electric arc producing and utilizing mechanism, a shield embodying means for automatically rendering the shield effective upon or preliminary to the formation of the arc.

A further object is to provide in connection with mechanism from the effects of which it is desirable to protect an attendant, a shield automatically operable to effective position upon the initiation of the operation of the said mechanism.

A further object is to provide a shield comprising a head-piece and means associated therewith whereby protective means may be

mechanically positioned before the face or eyes of the wearer, such means being controllable preferably from a distance so as not to require direct actuation or manipulation by the wearer.

Further objects and advantages will appear from the following description taken in connection with the accompanying drawings, in which

Fig. 1 is a front elevation of a form of shield embodying a head-piece adapted to protect the face and eyes of a workman from injury by rays emitted from an electric arc;

Fig. 2 is a rear elevation of parts of the head-piece shown in Fig. 1;

Fig. 3 is a section on the broken line 3—3 of Fig. 2;

Fig. 4 is a plan view of the shield showing a wiring diagram in connection therewith;

Fig. 5 is a diagrammatic view showing a different wiring arrangement; and

Fig. 6 is a perspective view illustrating the utilization of the shield in connection with an arc welding operation.

Referring to the drawings, 6 indicates a casing or frame, preferably of opaque non-combustible material such, for example, as a metal, aluminum being particularly suitable because of its lightness, within which are housed the moving parts of the shield. The casing 6 is shown as circular in front elevation, but its form may of course be varied widely as desired. As illustrated, it is provided with a flange 7 around the outer edge adapted to fit upon a shield member 8 of fibre board or other suitable opaque material to which the casing is secured as by fastening means 9.

The casing 6 is provided with one or more apertures or windows 10 suitably positioned and shaped so as to permit a workman wearing the head-piece to view through the said windows the operations upon which he is engaged. If desired, a transparent material such as pieces of clear glass 11 may be placed over these apertures and retained by engagement therewith of a plate 12 secured to the face of the casing 6.

Arranged centrally of the casing 6 and passing therethrough is a spindle 13 which may be screw-threaded and provided with nuts 14 adapted, if desired, to clamp together the casing 6 and the plate 12, which spindle

is formed on the interior of the casing with a journal 15 for the support of a shutter 16. The inner end of the spindle 13 may be supported in a bracket 18 secured to the inner face of the casing 6. The shutter 16 is so formed as to be capable of covering the apertures 10 and is provided with suitable light selective material 17 adapted in one position of the shutter to coincide approximately with the position of the window or windows 10 and permit the operator to look through both sets of apertures in order to view the work upon which he is engaged. The material 17 may be selected in accordance with the character of the effects from which it is desired to protect the wearer, and, for use with electric welding apparatus, may consist of colored glass of a type now generally employed in shields for this purpose.

In order to retain the shield closing means, as the shutter 16, in open position, that is, in a position wherein it is out of register with the apertures 10, a coiled spring 19 may be connected at one end to the shutter and at the other to a fixed part of the mechanism, as to the casing 6, the spring being arranged to exert a force on the shutter tending to rotate it to the open position. The extent of movement of the shutter in this direction may be limited by suitable stop means, for example, by engagement of the edge of the shutter with the edge of the bracket 18, as at 18' (Fig. 2).

The actuation of the shutter toward the closed position, that is, to a position in which the light passing through the windows 10 must also pass through the light selective means 17, is effected preferably by automatic means so associated with the arc producing and utilizing apparatus that the shutter will be closed slightly before the arc is produced. In the embodiment illustrated, the automatic means includes a pair of electro-magnets 20 whose pole pieces are extended as at 21 in proximity to the path of movement of the shutter 16, which latter will be of magnetic material. A yoke or band 22 of magnetic material may connect the two electro-magnets, which will then be oppositely wound, providing thus a substantially single horseshoe magnet the opposite poles of which will be positioned adjacent the ends of the shutter 16 when the latter is in its closed position. The windings of the electro-magnets may be connected through binding posts 23 to a suitable source of current in the circuit 24. A switch 25 is shown in the circuit 24 arranged to be actuated to closed position by an electro-magnet 26 placed in a circuit 27 arranged in shunt with the main circuit 28 supplying current to the arc 29.

In Fig. 5 I have illustrated a variant arrangement of wiring adapted for use particularly where the main circuit is normally

open and is arranged to be closed by an auxiliary circuit under the direct control of the operator. In this form the main circuit 30 is shown as including the work piece 31 the metallic electrode 32, an electrode clamp 33 having an insulated handle 34, and a switch 35. An auxiliary or control circuit 36 includes a switch 37, operable by a trigger or the like 38 in the handle 34, and a solenoid 39 operative, when energized, to close the main switch 35. Conductors 40, which may be arranged in shunt with the solenoid 39, complete the circuit through the magnets 20 of the shield operating mechanism.

It will be understood that the means for associating the action of the shutter with the operation of the arc producing mechanism may be widely varied in accordance with the character of the said mechanism or other circumstances. In some cases it might be desirable to eliminate the automatic feature and provide a push button or the like in convenient position for actuation by the workman, which arrangement might be the same as that shown in Fig. 5 if the solenoid 39 and switch 35 were eliminated. Various other ways will, of course, occur to one skilled in the art whereby the actuation of the shield to an operative or effective position may be made dependent upon the conditions obtaining in the apparatus in connection with which the use of the shield is desirable, and it is not my intention to limit my invention, generically considered, to any specific details either of such apparatus or of the operating mechanism.

The movement of the shutter to closed position may be limited by engagement of the edge of the shutter with the bracket 18, as already described with reference to the opening movement. It may be desirable, however, to provide means to prevent rebound of the shutter and to insure its retention in closed position during the flow of current in the shutter-actuating circuit. This may be accomplished, as shown in Fig. 2, by providing the pole pieces 21 with inwardly extending shoulders 21' with which correspondingly shaped portions 16' of the shutters will come in contact as the shutter reaches the limit of its movement, thus serving as a stop for the shutter and holding it at its limit of movement by the magnetic attraction, which, of course, is greatly increased as the surfaces come into contact. The breaking of the actuating circuit by destroying the magnetic field permits the opening of the shutter under the influence of the spring 19.

The shield 8 will be of shape and material suitable to protect the exposed portions of the face of the operator and, if desired, a skirt 41 may be attached to the edge of

the shield member to serve as a further protection to the operator against burns from the actinic rays of the arc or from sparks produced in connection with the utilization 5 of the arc. The shield as a whole may be supported upon the person in any suitable manner, as by the provision of side bows 42, top bow 43, and a chin piece 44 mounted upon the shield member 8, which bows and 10 piece may be adjusted in position or by bending in order to accommodate the supporting means to the contour of the head of the workman and adjust the sight openings to the eyes of the wearer.

15 In the operation of the shield as illustrated, the headpiece may be placed upon the head of the workman, the window or windows 10 being so located that the shield will not interfere with or obstruct the view of 20 the workman in connection with his usual preliminary work. However, upon the initiation of operation of the mechanism with which it is associated, for example, upon the flow of current in the control circuit to produce an arc, the shutter 16 will be rotated 25 to a position in which the light passing through the window or windows 10 must also pass through the selective medium 17 before reaching the eyes of the workman. 30 Inasmuch as the flow of current in the circuits as shown to produce the arc will take place before the arc is actually formed, it will be obvious that the closing of the shutter will precede by a slight but sufficient 35 interval the formation of the arc and there is therefore no danger that the light emitted by the arc will strike the unprotected eyes of the workman. Upon the interruption of the arc, the breaking of the circuit which 40 includes the shutter operating means will permit the return of the shutter to its non-obstructed position by means of the spring 19 or equivalent actuating device. The shield therefore provides a means for insuring 45 the protection of the workman from injury by light or other emanations, sparks, flying particles, or other analogous effects incident to his occupation, without requiring any attention on the part of the wearer other than the attaching of the shield in 50 suitable position upon the person, thereby not only freeing the hands of the wearer for the work upon which he is engaged, but also preventing occurrence of injury by reason of any negligence or inattention of the operator himself.

It will be understood that the selection 55 of material for the protective parts of the shield, head-piece, or helmet, will depend upon the particular relation in which it is to be employed, the materials being such, of course, as will intercept the particular effects, emanations, particles, etc. from which the wearer is to be protected. The automatic 60 actuation of the shield may also be ren-

dered responsive to any desired conditions incident to the existence of the deleterious agents from which protection is desired by merely placing the actuation of the shield closing means under the control of suitable 70 devices sensitive to the said conditions.

Many changes may be made also in the mechanical details of the shield without departing from the spirit and scope of the invention and therefore I do not desire to 75 be limited in any way by reason of the foregoing description to the specific details of construction therein set forth except as may be required by the language of the appended 80 claims in view of the prior art.

I claim:

1. A shield adapted to be carried upon the person and comprising protective means adapted to be rendered effective or non-effective to protect the person from injury, 85 and means automatically operable upon the occurrence of conditions injurious to the person for rendering the said protective means effective.

2. A shield adapted to be carried upon the person and comprising protective means adapted to be moved to position for protecting the person from injury, and electrically operated means automatically actuated to move said protective means to protecting 95 position upon the occurrence of conditions conducive to injurious effects.

3. In combination with electric arc apparatus, a shield adapted to be rendered effective to protect the person from effects 100 incident to the arc, and means associated with the arc-producing circuit or circuits for rendering said shield effective.

4. In combination with electric arc apparatus, a shield comprising a head-piece, 105 means thereon movable to position to protect the wearer from effects incident to the arc, and means actuated preliminary to the production of the arc for moving said movable means to protective position.

5. A shield comprising a head-piece having means movable to and from an eye-protecting position and electrical means for actuating said first mentioned means to protecting position.

6. A shield comprising a head-piece having one or more windows therein, a shutter adapted to be positioned before said window or windows, means for moving said shutter to closed position, and magnetic 120 means for retaining the shutter in closed position.

7. A shield comprising a head-piece having one or more windows therein, a shutter adapted to be positioned before said window or windows, spring means for moving said shutter to open position, and electromagnetic means for moving said shutter to closed position.

8. In combination with electric arc ap-

paratus, a shield comprising a head-piece having a window therein, a shutter movable to and from a position in register with said window, electro-magnetic means for moving 5 said shutter to closed position, means acting in opposition to said electro-magnetic means for moving said shutter to open po-

sition, and connections arranged between said arc apparatus and said electro-magnetic means adapted to cause actuation of said 10 last-mentioned means upon the supplying of current to said arc.

In testimony whereof I affix my signature.
ELVIN S. GOOD SPEED.
